UNITED STATES PATENT OFFICE.

GIORGIO ADELMO, OF SPRING VALLEY, ILLINOIS.

ELECTRIC VIBRATOR FOR RAZORS AND THE LIKE.

Application filed March 17, 1924. Serial No. 699,914.

To all whom it may concern:

Be it known that I, GIORGIO ADELMO, a subject of the King of Italy, and a resident of Spring Valley, in the county of Bureau and State of Illinois, have invented a new and useful Improvement in Electric Vibrators for Razors and the like, of which the following is a full, clear, and exact description.

10 My invention relates to improvements in razor operating devices, and it consists in the combinations, constructions, and arrangements herein described and claimed.

15 An object of my invention is to provide a device for supporting and vibrating a razor blade for use in shaving the beard.

20 A further object of my invention is to provide a razor operating device in which the razor clamp may be removed therefrom and the ordinary type of vibrator appliance substituted.

25 A further object of my invention is to provide a device of the type described in which particular novel means is employed for housing the internal mechanism to assure against unintentional and discordant vibration.

30 A further object of my invention is to provide a device of the type described in which the internal mechanism for vibrating the razor clamp is housed in an insulating casing, thereby insulating all of the electrical parts from the hand of the operator, and also providing a heat insulating medium about the internal mechanism.

35 Other objects and advantages will appear in the following specification, and the novel features of the invention will be particularly pointed out in the appended claims.

40 My invention is illustrated in the accompanying drawings, forming part of this application, in which

Figure 1 is a front elevation of an embodiment of my invention,

45 Figure 2 is a partial side elevation of the mechanism illustrated in Figure 1,

Figure 3 is a top plan view of the mechanism illustrated in Figure 1,

50 Figure 4 is a front elevation of a part of the mechanism illustrated in Figure 1, a portion of the casing being removed therefrom, and

Figure 5 is an enlarged sectional view along the line 5—5 of Figure 4.

55 In carrying out my invention I make use of a casing comprising two cooperating

parts A and B. These parts are constructed of molded composition, such as bakelite or other well known compositions, having insulating properties. The casing is narrowed as shown at 1 upon its side walls so as to facilitate the holding of the casing in the hand of the operator in such a manner as to preclude any slipping of the device due to its inherent vibratory properties. 60 65

The casing is further provided with vents 2 arranged in symmetrical groups, (see Figure 1) through the major walls of the cooperating parts A and B. The purpose of these vents is to permit air to circulate 70 through the internal mechanism of the device and prevent overheating of the mechanism.

The mechanism employed for imparting vibratory motion to the razor clamping 75 mechanism consists in a substantially U-shaped laminated core having protrusions 4 at each end of the rearward part or heel of the core, (see Figure 4). These protrusions 4 form an ingenious means for preventing unintentional movement of the core 3 relative to the casing. This guard against movement of the core is brought about by the provision of a recess R in the adjacent side walls of the parts A and B having the shape of the rearward portion of the core 3, including cavities C for receiving protrusions 4. In this manner, the core 3 is securely clamped against movement when the parts A and B are secured together as 80 85 90 by means of binding screws 5, provided for that purpose.

Each of the branches 6 and 7 of the core 3 has wound thereupon a coil of current conducting wire 8. These coils 8 are connected in series with one another at 9, and one of the leads 10 therefrom is connected directly with a conductor 11, the other end of which is connected with a suitable attachment plug, (not shown). This attachment plug is of the ordinary type, such as used for stand lamps, flat irons, and the like. The opposite lead 12 of the coils 8 is connected to one terminal post 13 of the switch 14. The opposite terminal post 15 of the switch is connected to the remaining connection wire 16 which is in turn connected with the aforesaid attachment plug. 100 105

The connecting wires 11 and 16 are both run through a flexible lead 17 formed of a coil of tightly wound spring wire, which is projected through registering channels 18 110

in the parts A and B, at the lower end thereof. The inner end of the spring lead member 17 is enlarged somewhat to prevent its movement exteriorly of the casing.

6 The armature upon which the razor supporting clamp is supported is comprised in a band of magnetizable metal 19 having one end thereof projected through registering channels 20 of the parts A and B, and is 10 substantially angular in cross section. The armature 19 is arranged to lie directly in front of the branches 6 and 7 of the core 3, but not normally touching these branches. The lower end of the armature 19 is bent and 15 is arranged to lie directly upon the innermost side of the lower wall of the parts A and B as shown at 22. A binding plate 23 is disposed upon the outer side of the lower wall of the parts A and B in registration 20 with the part 22 of the armature 19, and machine screws 24 are projected through the plate 23, the lower walls of the parts A and B, and are threaded directly into the portion 22 of the armature 19. This particular 25 means for mounting the armature 19 is one which I deem of particular importance, since it provides a rigid support for the lowermost end of the armature, which is an armature vibrating at an exceedingly high period, 30 and also serves to effectively clamp the lowermost portions of the parts A and B against movement apart from one another, thereby doubly assuring the separation of the casing at this point, which might occur 35 if some such means as just described were not devised.

It is well to note at this time that my improved razor operating device is intended 40 for use upon the ordinary alternating current service line, in which the frequency of alternations is ordinarily fixed at 60 cycles per second. It will therefore be apparent 45 that the period of vibration of the armature is most exceedingly high, and that rigidity in mounting the internal parts is of utmost importance, particularly in a device of this type.

The switch 14 is more clearly shown in 50 Figure 5, and the internal working parts of the device are mounted upon the disc 14^a. This disc 14^a is arranged to be partially received within an enclosure formed by the provision of an inwardly extending annular flange 25 on the innermost wall of the part A. An opening 26 is provided through the 55 wall of the part A in registration with the axis of the annular flange 25 to permit the projection of the stem 27 of the switch mechanism mounted upon the disc 14^a. The outermost end of the stem 27 has a knob 28 thereupon, the switch being disposed exteriorly of the casing, and may be manually operated by the turning of the knob so as to 60 rotate the commutator 29, forming a part of the aforementioned switch mechanism.

My improved electric vibrator is primarily intended for operating a razor for shaving, yet the device may be used with equal advantage for the operation of any one of the many well known vibrator appliances, such 70 as cups, balls, combs and the like, for the purpose of facial and scalp massage. The following is a description of one form of razor holding device which, while shown in this application, is claimed in my co-pending 75 application Serial No. 744,298.

The razor holding clamp which is arranged for disposition upon the angular portion 21 of the armature 19 consists in a body member 30 having an angular loop-shaped 80 member 31 at one end thereof which is arranged to fit over the angular part 21 of the armature. A thumb screw 32 projected through the body member 30 adjacent to the loop portion 31, provides means by which the loop 31 may be slightly contracted, and in this manner securely clamps the body member 30 upon the armature 19.

The body member 30 is provided with a depending member arranged to yieldably 90 engage with the handle 33 of the ordinary type of razor 34. This depending member consists in a pair of spring clamps 35 carried by the body member 30 and disposed at a slight angle with respect to the axis of 95 the part 21 of the vibrator 19. A separator 36 is disposed between the spring clamping members 35 and is arranged to extend slightly below the lowermost ends of these members. The lowermost ends of the members 100 35 are dished outwardly as shown at 37, so that the split handle 33 may easily be moved beyond the lowermost ends of the spring clamping members 35 when placed astride 105 the separator 36 in the manner shown in Figure 2. The clamping members 35 function solely to yieldably hold the handle 33 of the razor against both longitudinal and lateral movement relative to the body member 30 of the clamping mechanism.

Means for supporting the blade 38 of the razor 34 when first inserted in a suitable guard 39 is provided as follows: A strap 40 is hingedly mounted at 41 to the body member 30 in such a manner as to permit the strap 40 to be moved to the position shown in full lines in Figure 1, or to the position shown in dotted lines. In both cases the strap 40 lies in a plane substantially parallel 115 with the separator 36.

This strap 40 has disposed at its outermost end a spring pressed clamp 42, the work engaging part 43 of which is in turn pivotally connected to the clamping member 42 so as to completely conform with the irregular configuration of the neck 50 of the razor 34. It is therefore evident that the razor blade 38, together with its guard 39 may be firmly secured against movement 125 upon the body member of the clamping 130

member so that the vibratory motion imparted to the body member 30 by the armature 19 when alternating current is flowing through the coils 18 will be evident by an

5 almost imperceptible movement of the blade laterally.

It should be noted at this time that the razor may be employed without the guard 39 if desired. However I recommend the 10 use of a guard 39 with the blade 38.

From the foregoing description of the various parts of the device, the operation thereof may be readily understood. The 15 person using the device will first manually place the guard 39 between the strap 40 and the spring pressed clamping member 42 so that the blade 39 is securely fixed against movement relative to the strap, and therefore to the body member 30.

20 The strap 40 is then hinged to the position shown in full lines shown in Figure 1 or to the position shown in dotted lines, depending upon which side of the face is to be shaved, and the blade 30 is hinged up-

25 wardly so that the split portion thereof may lie astride the separator 36 and be received between the spring pressed clamping members 35 which will securely hold the handle against movement both longitudinally and laterally. The switch mechanism operated 30 by the knob 28 is then closed so as to permit current to flow through the coils 8, thereby causing a magnetic field about the branches 6 and 7 of the core 3, and consequently caus-

35 ing the exceedingly high vibratory movement, which movement in turn will be imparted to the blade 38 and move the blade laterally. The blade is then moved over the face in precisely the same manner as though 40 the razor operating device were not employed, except that a swift stroke of the razor is not necessary.

Obviously my improved vibrating mechanism may be used for the purpose of supporting a suitable clamping device upon the 45 stem 21 for holding ordinary types of safety

razor, mechanical vibratory appliance or the like, without in any way departing from the spirit and scope of the invention.

I claim:

1. A device of the type described comprising a casing of insulating material consisting of two complementary parts, said parts having irregular recesses in one inner side wall thereof in registration with one another a magnetizable core arranged to be supported in said casing and partially received in said irregular recesses, whereby said core may be securely fixed against movement relative to said casing by means of said recesses, magnet coils disposed upon said core, an armature for said core arranged to partially extend exteriorly of said casing, and means for securing said armature to the inner wall of said casing at its lower end, said means also serving to securely bind the complementary parts of said casing to one another.

2. A device of the type described comprising a casing consisting of two complementary parts, said casing having vent openings through the side walls thereof, said parts having registering irregular recesses, a magnetized core supported in said casing and partially received in said irregular recesses, whereby said core may be securely fixed against movement relative to said casing by means of said recesses, an armature for said core arranged to partially extend exteriorly of said casing, magnet coils disposed upon said core, electrical connections for said magnet coils extending exteriorly of said casing, a binder plate and screws projected through said binder plate and through each of the complementary parts of said casing, said screws being further arranged to engage with threaded openings provided in said armature, whereby said armature is held in place and the complementary parts of said casing are held in engagement with one another.

GIORGIA DELMO.
